UNITED STATES PATENT OFFICE

ALBERT BIGIO, OF NEW YORK, N. Y.

TRAFFIC-SAFETY DEVICE

Application filed September 25, 1924. Serial No. 739,842.

My invention relates to an improvement in railway crossing protector devices and is especially adapted to the protection of vehicular traffic, and incidentally railway traffic, at points where the road for vehicles and the roadbed of the railway intersect and commonly known as grade crossings.

One of the novel features of my device relates to a method of signalling, for both forms of traffic, which is initiated by the railway traffic only, and through such initiation, to cause a certain automatic sequence of events within the system herein outlined to occur, in a manner to be hereinafter described in detail.

Another distinct advantage of my device comprises the utilization of means which, while acting as guard gates against encroachment of rail right of way, after the signals and sequences have been initiated, whereby said guarding means will act as a sweep, with a tendency to clear the grade crossing or rail right of way of obstructions.

Another advantage of my device is that in the event such guarding devices are interfered with, in the normal operative function of closing the rail right of way as above outlined that this interference with the function thereof or the preventing of such functioning is immediately transmitted by signals to the engineer of the on-coming train thereby permitting him to note such warning and to bring the train to a standstill before reaching the grade crossing.

Other advantages of my device consist in the manner of clearing the signalling system after the train has left the grade crossing and the automatic restoring of the system to readiness of operation for a complete cycle of operation.

Another advantage of my invention, relates to the construction, whereby trains are permitted to operate in either direction and the system will operate as described. This and other features will appear as the specification herein proceeds.

In the drawing Fig. 1 is a fragmentary plan view of a railway grade crossing showing the gates in operative closed position against vehicular traffic.

Fig. 2 is a side elevation of either of said gates in an open position for permitting the vehicular traffic to cross the rails.

Fig. 3 shows one form of a type of mechanism for operating to close and open the said guard gates.

Fig. 4 shows an end view of a train vehicle in operative position with the operative contacts.

Fig. 5 is a diagrammatic hookup of the electric circuits whereby the train control mechanism will cause to operate, and

Fig. 6 is a separate diagrammatic view of the electric signal control system shown apart from Fig. 5 for the purpose of clarity.

In the plan view, Fig. 1, there is shown a railway roadbed comprising rails and ties, generally denoted by R, and traversing this roadbed at right angles thereto is a vehicular right of way of any desirable width, generally denoted by V, between the arrows on both sides.

As indicated in Fig. 1, the gates G¹ and G², for guarding the rail crossing against vehicular traffic, are shown closed, they being supported for swinging movement upon gate post P at the top of which is mounted a visual signalling device such as any suitable type of railway lantern L having on opposite sides the usual red and green lights for indicating danger or clear signals. In the position as shown, the gates are closed against vehicular traffic, and in this instance the green lights show up and down the rail right of way and the red lights therein show the opposite sides against vehicular traffic, thereby giving warning. These lights will be continuously lighted so that when the gates are open, then the red lights show against the rail traffic and the green lights show clear for vehicular traffic.

As a means for acting as a stop for the operating gates, there is arranged on the opposite side of the railway, and opposite to the operative mechanism for the gates, which will later be described, a suitable form of gate stop S which in the present instance is constructed of a piece of plain angle-iron which may be suitably buried in the ground adjacent the roadbed as at A, Fig. 2. The guard gate

may have arranged thereon, a sign having the word "Stop" thereon or its equivalent on both sides of said sign so that in stop position either against the train or vehicular traffic, 5 the sign contributes the further warning against movement of either traffic, according to setting and this sign is indicated at B, Figs. 1 and 2.

One form of preferred means for operating to open and close gates, upon actuation of the control mechanism there is shown in Fig. 3 a concrete pit C which is preferably formed in the ground below the level of the roadbed R and adjacent the same on opposite sides as shown in Fig. 1. This pit is preferably made in such a manner as to make it tamper and water proof. Within the pit I have located an electric motor generally denoted by E in Figs. 3 and 5 and this electric motor has arranged upon one end of its armature shaft, a worm drive D which in turn meshes with a worm wheel W which is frictionally engaged upon a jack shaft J which is preferably rotatably held in a bracket support K which is suitably and firmly affixed to the bottom of the pit. Under certain conditions the worm wheel W is free to revolve with the shaft J owing to the arrangement of a friction drive means M shown on the left side thereof, said friction drive in turn being mounted upon a bevel gear sleeve N mounted within the bearing portion of the bracket K, and the bevelled gear O which is affixed to said sleeve is thereby caused to revolve by the motor driving the said worm wheel W. In turn the bevelled gear O meshes with a bevelled gear sector Q which is in turn mounted rigidly at the lower end of the tubular stop gate post P, said tube being indicated 30 as at T, Figs. 2 and 3.

In the preferred form of construction, and in order to eliminate certain parts which may otherwise be used in their installation, I prefer, owing to the short time in which said gates will be in use in guarding the rail right of way, that the motor shall continue to rotate and act as locks, during the period of operation of the gates as closures until a 45 change of cycle occurs and they return to their normal positions, to permit vehicular traffic to cross.

To this end, when the motor E revolves it causes the worm wheel W to revolve and this in turn drives the gear O which in turn drives 50 the sector Q, and according to the direction of the rotation of the motor E the gates will be driven to their full operative closed or open position and will be thereby stopped in their position by the gate stops S whether the gates 55 are in open or closed position against vehicular traffic.

Upon reaching either one of these positions and until such period as the sequence of control, later to be described, is completed the 60 motors will continue to run, driving the worm

wheel W and its cooperative mechanism until such time as the gates have reached the desired controlling position, whereupon the gates will stop but the motor will continue to drive the worm wheel W and the friction 70 mechanism will thereupon slip until the guarding operation has been completed and thereafter the cycle is reversed and the gates return to normal open vehicle position, after which the motor will cease rotating leaving 75 the gates in the desired position.

As a means for causing the motor to commence operating upon the rotating activity of the system and to later cause the motor to cease operating upon the completion of the 80 cycle, I have herein outlined, in more or less diagrammatic form, one of such circuits as would operate the rail control mechanism as above described.

By referring to Fig. 5, there will be noted 85 a pair of conductive main wires 1 and 2 and which wiring may be continued along the rail right of way for furnishing the desired electric power from any suitable source, not shown. From the main 1 and 2 there leads 90 two connections 3 which run to the interior of the pit and from these upwardly through the tube of the shaft T to two warning signal lights L and these two lights are joined in series by another wire 4 so that these lights 95 are continuously lit so that their opposite red and green signals may exhibit in favor of or against traffic according to the position of the gates G.

Leading to another point, shown in the 100 right hand side of the drawing are another pair of electric conduits 5 and 6 both of which run to opposite sides to an oscillating switch generally denoted by 7, in the present instance this form of switch being shown as 105 pivoted at 8 for operating either to the right hand as shown or on the left hand as shown, thereby closing or opening the circuits which are controlled by switch points 9 and 10 or an equivalent pair of switch points which 110 are shown in the drawing as being in contact or under the lever 7, by dotted lines.

This oscillating lever may be mechanically or electrically connected to a switch arm control mechanism preferably placed at the opposite end of said control circuit and this being generally denoted by a base 10' having a pivotally operated crank arm 11 and an operative connecting means between both said switch and arm control means comprising a connecting rod 12 so that any movement is transferred to the switch 7—8—9—10 from the control arm 11. 115

In the position as shown of switch 7, the current through the main 1—2 flows through the lead 5 and down through the leads 13, 14, 15, 16 and 17 and the terminal end of these wires is connected to oppositely disposed contact elements generally denoted by 18 and 18'. 120

On the opposite side of the switch lever 7 as shown, the current passes from the main through the lead 6, 19, 20, 21 and 22, the upper end of these wires terminating in connection with control contacts 23 and 23'.

Inasmuch as all of these control contacts are separated from one another by insulating means, as shown, obviously no current can pass therebetween, and therefore while the switch 7 and its companion 11 are in the pre-set position, as shown and as set, in readiness for operation, they are, in operation closed by a bridging contact means which is carried by the train vehicle X as indicated in Fig. 4 and which will be later described.

From the ends of contacts 29-29', are two leads 24, 25 which in turn are connected to one terminal each of the two motors E. The opposite terminals of the motors E, are in turn connected to leads 26, 27, which are connected to insulated contacts 28-28, Fig. 5, at right side of diagram, as shown. These last contacts are not in electrical connection with the source of power, except as will be hereinafter described.

At the left hand side of diagram Fig. 5, is shown a sliding contact control element similar to that just described, and its manner of hookup is as follows; the insulated contacts 29-29 are connected to each of the motor terminals, in series, by leads 30, 31, and the opposite terminals of each motor are connected by leads 32, 33 to contacts 34, 34, respectively, so that in effect, through this control circuit, the motors E are arranged in reverse series, that is to say that, according to approach of train, in either direction, with its circuit closing shoe, to be later described, the motors E are energized to cause a right hand, or a left hand rotation of the motor armatures, according to which group of contacts first energize the motors, which then determines the sequence of operation of the gates, starting from either side or end of the control system, in conjunction with the last position of the switch control mechanisms 7-8-9-10 and 10'-11.

By referring to Fig. 4, there is therein disclosed an end elevation of a railway vehicle, generally denoted by X, which has attached thereto a circuit control means for causing the sequential operation of the foregoing described safety mechanism. While it is here shown more or less diagrammatically, the prime essentials of this simple form of actuator may be fully understood from the following: At any convenient point at the underside of the railway vehicle, and preferably, this may be on the motive vehicle, there is arranged any desired form of support 34', which may carry at its outer ends, for operation in either running direction of the train, a switch throwing means 35-36. This last arrangement cooperates with the control

switch 7-8-9-10 to energize the system to initiate action, upon approach of a train to the grade crossing protected by my device.

Upon the support 34', is located an insulator plate 37, which in turn supports 70 bridging contact means 38, 39, which when in operative position, are in a plane to contact with the circuit control contact means 18-29' and 23-28 or 18'-29 and 23'-34, and by such bridging, sliding contact to energize all foregoing described circuits or to cut out the same from the source of power 1-2.

The source of power or main 1-2, may be continued to other points along the line to 80 energize like crossing controls, as herein described.

The action or operation of my device is as follows:

The rail guard-gates G in Fig. 5 are guarding the rail right of way, as shown, permitting vehicular cross traffic in the direction of the arrows 41, both ways, but blocking rail traffic in the sense that the gates in this position, are in control of a signal-light system, 85 later to be described, which shows "clear" to vehicular traffic but "danger" to rail traffic.

Upon the approach, to the grade crossing, by a train, and at any sufficient distance therefrom, the train by the previously noted mechanism, first strikes the control switch 7-8-9-10 and sets it to close the circuit as shown, which includes, from the main 1-2, the following; leads 5-6, 13-19, 14-20, contacts 18-18 and 23-23, contacts 18'-18', and 23'-23', through leads 15-20, 21-16. At this point the circuit is not closed, but is operatively closed upon the train then reaching the control contacts 18-23-28-29', 100 first group, whereupon the contact bridge 38 closes contacts 23-28, and simultaneously contact bridge closes contacts 18-29'. 105

The foregoing action, through the leads, etc. previously noted causes the first gate G¹ to close through the operation of the lower shown motor E, which is operatively connected to said gate as shown in and described for Fig. 3, thus causing the said gate to move to its vehicular barring position Y, as shown in dotted lines in Fig. 5. In sequence, thereafter, the upper motor E is then actuated by the second group of control contacts being closed by the bridge 38 closing the control contacts 18-29', thus energizing said motor E and through the operative connection set forth for Fig. 3, the upper gate is caused to close the opposite side of the rail right of way against vehicular traffic.

Upon the train leaving the control contact zone, the motors E cease to operate leaving the two gates in closed position, but clear for the passage of the train.

When the train has passed the crossing, at 125 a predetermined point, it engages with the

second set of control contacts 18'-23' etc., and proceeds to operate these in the same manner as described for the first set of control contacts, with the difference, however, 5 that the contacts 18'-23', and 29-34 are so arranged that they cause the current to enter the motors E in a reverse direction thus causing the gates to be operated back to original open vehicular traffic position.

10 This is accomplished by the train bridge contact closing, first the control contacts 29-34 in the advance group, thus operating to cause the lower shown motor E to open its gate, and then sequentially to advance upon 15 and bridge the second control contacts 29-34, thus energizing the upper shown motor E also in a reverse direction, causing the upper gate G² also open to vehicular traffic and closed against train traffic. Thereafter as 20 the train leaves the control zone, the motors E cease to operate and the system is left in condition to be operated by any train coming from either direction. If it so happens that the next train also moves into the control 25 zone from the same direction as the previous train, i. e., in the direction of the arrow 40, the system is set for the above described sequence of operation. However, if a train should come from a direction opposite to 30 the arrow 40, then the switch control arm 11 is intercepted, moved to its opposite angular position, and through the connecting rod, or equivalent means 12, the switch lever 7 is thrown to a position opposite to that shown 35 in Fig. 5, thus closing contacts 9-10 and setting the entire circuit into a reverse current control, thereby causing the entire circuit and apparatus to respond in the same sequence to operate the gates to close and open 40 under the control of said oppositely moving train.

In the last noted instance the train contact bridge 37, after which 7 has been thrown, operates to bridge control contacts 23'-34 to 45 operate the upper motor E to close the gate G² against vehicular traffic, then the second control contacts 23'-34 operate the second lower motor E, closing lower gate G¹ against vehicular traffic, and as previously described 50 for the train travelling in the direction of the arrow 40, the first control contacts 18'-29 of the second group open gate G², second control contacts 18-29' open second gate G¹ to vehicular traffic and the system is again in 55 readiness to operate under the influence of a train travelling in either direction.

It will be noted from the foregoing description that the train initiates a sequence of controls whereby its passing through the 60 control zone in either direction causes a predetermined series of operations to take place regardless of its direction of movement, and is at all times set to operate.

In addition to the foregoing, and as a 65 means for giving double warning, one to the

vehicular traffic and one to the train traffic upon any change occurring in the operative condition of my system or upon the occurring of some undesirable condition of operation, I have provided in association with my system 7 an alarm arrangement, consisting of visual (lights) and audible (bell or horn) warning devices. To this end reference is had to Fig. 6 in which, for clearness, such alarm circuits are shown separately from the traffic control 7 circuits although under the control thereof as will now be pointed out.

As previously referred to, the gate posts P being hollow, wiring 3-4 permits the light signals L thereon to be permanently lit, and 8 according to gate position to show "clear" or "danger" in either direction of cross traffic. In addition, I have provided means for enabling the engineer of the train to receive a check signal, while in transit, to assure him 8 that the safety system is operating, and in sufficient time to permit him to stop his train, when warned of the non-functioning or interference with the system. Substantially simultaneously therewith a warning of train 9 approach is given to vehicular traffic by an audible signal, such as a horn 41, Fig. 6, and also a visible warning by the heretofore described lights L.

In Fig. 6, the gates G¹-G², are shown as blocking rail traffic, as in Fig. 5, the posts P having arranged at any suitable point warning control switch arms 42-42 affixed thereto, to operatively oscillate with the gates, from one position to the other, and at the terminal points are located contacts 43-44, the contacts 44 being preferably arcuate and separated slightly from the contacts 43, so that a slight movement of the gates will close the light signal and horn circuits, and thus 1 immediately give warning to vehicular traffic of train approach and closure of right of way. The current therefor is supplied through the leads 3 from the main 1-2, when the posts P are in either position.

In the post switch position shown in Fig. 6, only one set of lights are in circuit, such as z; these all being red lights, and are set against the train, showing that the track is blocked. These lights, however, in actual practice are 1 placed at interval of about one third of a mile apart, and the control switch 7-8-9-10 and arm 10' still further away so that the first contact of the train with the system will cause the gate posts P to operate, whereupon 1 the gates shift, and the lights z go out and the second circuit or green lights z' light up, thereby indicating to the engineer that the crossing is properly guarded.

If the crossing is blocked however, and the gates are interfered with so that they cannot close then the warning red lights z remain lit, and the engineer brings his train to a stop.

The train in leaving the crossing control section, as previously set forth, causes a re-

versal of the entering cycle, and upon the return of the gates to initial position, the lights clearing the vehicular road are set and the red lights blocking the rail right of way are reset and the system is again ready for further train operation.

Modifications may be made in the details of the mechanisms and circuits herein disclosed without departing from the spirit of the herein disclosed invention, or exceeding the scope 10 of the appended claims.

I claim:

1. In a safety device for a crossing formed by the intersection of two kinds of traffic, in combination, movable means adapted for sequentially blocking and permitting passage of said traffic at said crossing, means operated by electricity for moving said blocking means, a first electric contact means arranged 15 in the line of passage of one of said traffics and electrically connected with said electrically operated means for moving, a second electric contact means arranged in the same line of traffic as the first contact means and 20 electrically connected with said electrically operated means for moving, means for supplying electric current, and a switch cooperating between said current supplying means and said first and second contact means, said 25 switch being operated by a vehicle moving along the line of traffic which has said electric contact means therein, said vehicle being provided with means for contacting in turn said first and second contact means, contact 30 of said means of the vehicle with the first electric contact means causing operation of said electrically operated means for moving said blocking means from position blocking the line of traffic having said electric contact 35 means therein to position for blocking the other line of traffic and contact of said means of the vehicle with said second electric contact means causing operation of said electrically operated means for moving said blocking 40 means from its last mentioned blocking position to its former blocking position.
2. In a safety device for a crossing formed by the intersection of a line of track controlled traffic and a line of road traffic, in combination, means arranged at opposite sides of the track controlled traffic for sequentially blocking the track controlled and road traffic means operated by electricity for moving said blocking means, electric contact means 45 arranged in the line of the track controlled traffic and distant from said blocking means laterally thereof and electrically connected with said electrically operated means for moving, electric contact means arranged in 50 the line of the track controlled traffic and distant from said blocking means laterally thereof in direction opposite the first mentioned contact means and electrically connected with said electrically operated means from moving, means for supplying electric current, and 55 a switch cooperating between said means for supplying current and said first and second mentioned contact means, said switch being operated by a moving track controlled vehicle provided with means for contacting in turn said first and second contact means, contact of said means of the vehicle with said first contact means causing operation of said electrically operated means for moving said blocking means from position blocking the track controlled traffic to position for blocking the road traffic and contact of said means of the vehicle with said second contact means causing operation of said electrically operated means for moving said blocking means from position blocking the road traffic to their former position.
3. In a safety device for a crossing formed by the intersection of a line of track controlled traffic and a line of road traffic, in combination, gates for sequentially blocking and permitting passage of said traffic at said crossing means operated by electricity for moving said gates, a first assemblage of electric contacts 85 arranged in the line of the track controlled traffic and electrically connected to said electrically operated means for moving, a second assemblage of electric contacts arranged in the line of the track controlled traffic and electrically connected with said electrically operated means for moving, means for supplying electric current, and a switch cooperating between said means for supplying current and said first and second contact assemblages, said 90 switch being operated by a moving track controlled vehicle provided with means for contacting in turn said first and second assemblages, contact of said means of the vehicle with said first assemblage causing operation of said electrically operated means for moving said gates from position blocking the track controlled traffic to position for blocking the road traffic and contact of said means of the vehicle with said second assemblage causing operation of said electrically operated means for moving said gates from position blocking the road traffic to their former position.
4. In a safety device for a crossing formed by the intersection of a line of track controlled traffic and a line of road traffic, in combination, gates arranged on opposite sides of the track controlled traffic for sequentially blocking and permitting passage of said traffic at said crossing, an electric motor for each of said gates for moving the gate, a first electric contact means arranged in the line of the track controlled traffic and electrically connected with both said motors, a second electric contact means arranged in the line of the track controlled traffic and electrically connected with both said motors, means for supplying electric current, and a switch cooperating between said means for supplying current and

- rent and said first and second electric contact means, said switch being operated by a moving track controlled vehicle provided with means for contacting in turn said first and second electric contact means, contact of said means of the vehicle with said first contact means causing operation of said motors for moving said gates from position blocking the track controlled traffic to position for blocking the road traffic and contact of said means of the vehicle with said second contact means causing operation of said motors for moving said gates from position blocking the road traffic to their former position.
5. In a safety device for a crossing formed by the intersection of a line of track controlled traffic and a line of road traffic, in combination, posts on opposite sides of the track controlled traffic and axially rotatable in opposite directions, a gate on each post swingingly movable in opposite directions by rotation of the post, electrically operated means for rotating said posts, a first assemblage of electric contacts arranged in the line of track controlled traffic on one side of said gates and electrically connected with said electrically operated means for rotating, a second assemblage of electric contacts arranged in the line of the track controlled traffic on the side of said gates opposite the first mentioned side and electrically connected with said electrically operated means for rotating, means for supplying electric current, and a switch cooperating between said means for supplying current and said first and second assemblages, said switch being operated by a moving track controlled vehicle provided with means for contacting in turn said first and second assemblages, contact of said means of the vehicle with said first assemblage causing operation of said electrically operated means for rotating for moving said gates from position blocking the track controlled traffic to position for blocking the road traffic and contact of said means of the vehicle with said second assemblage causing operation of said electrically operated means for rotating for moving said gates from position blocking the road traffic to their former position.
6. In a safety device for road crossings, in combination, means movable in opposite directions for sequentially blocking intersecting lines of traffic, first and second electric contact means located in one of the lines of said traffic and adapted for successive operation, means for supplying electric current, and means cooperating between said current supplying means and said blocking means and including means for moving a switch, said switch being operated by a vehicle moving in the line of traffic having said electric contact means therein, said vehicle operating in turn said electric contact means, operation by said vehicle of said first electric contact means causing movement of said blocking means in one direction and operation by said vehicle of said second electric contact means causing movement of said blocking means in direction opposite to the first direction.
7. In a safety device for road crossings, in combination, means movable in opposite directions for sequentially blocking intersecting lines of traffic, electrically operated means for moving said blocking means, first and second electric contact means located in one of the lines of said traffic and adapted for successive operation and electrically connected to said electrically operated means for moving, means for supplying electric current, and a contactable switch cooperating between said means for supplying current to said first and second electric contact means, said switch being operated by a vehicle moving in the line of traffic having said electric contact means therein, said vehicle being provided with means for contacting in turn said first and second electric contact means, contact of said means of the vehicle with said first contact means causing operation of said electrically operated means for moving said blocking means in one direction and contact of said means of the vehicle with said second means causing operation of said electrically operated means for moving said blocking means in direction reverse to the first direction.
8. In a safety device for road crossings, in combination, gates movable in opposite directions for sequentially blocking intersecting lines of traffic, first and second electric contact assemblages located in one of said lines of traffic and spaced apart therein for operation in turn, said assemblages including groups of electric contact members, said groups being adapted for successive operation, means for supplying electric current, and means cooperating between said current supplying means and said gates and including electrically operated means for moving the gate and a switch for connecting the current supplying means to the assemblages, said switch being operated by a vehicle moving in the line of traffic having said assemblages therein, said vehicle operating in turn said assemblages by operating successsively the groups of contact members in the assemblages, operation by said vehicle of said first assemblage causing movement of said gates in one direction and operation by said vehicle of said second assemblage causing movement of said gates in direction opposite to the first direction, successive operation by said vehicle of the groups of contact members included in the assemblages causing movement of one of the gates in advance of the other gate when the gates are moved in either direction.
9. In a safety device for a road crossing formed by the intersection of two lines of

traffic in combination, an assemblage of electric contacts arranged in one of said lines of traffic and consisting of a plurality of groups of contact members, means in the other line of traffic successively movable to close the same, said closing means being connected to said groups, said groups being adapted for successive operation of the groups, and means for successively operating the groups and 10 appurtenant to a vehicle moving along said line of traffic.

10. In a safety device for a road crossing formed by the intersection of two lines of traffic, in combination, an assemblage of electric contacts arranged in one of said lines of traffic and including a plurality of groups of contact members, each of said groups consisting of a plurality of contact members arranged parallel to each other and spaced 15 apart and extending parallel to said line of traffic and operable by bridging said contact members, gate means in said other line of traffic successively movable, said groups being operable successively to close said gate means, 20 and bridging means appurtenant to a vehicle moving along said line of traffic and engageable with said groups for successively operating the groups.

11. In a safety device for road crossings, in 30 combination, means successively movable in opposite directions for sequentially blocking and clearing intersecting lines of traffic, warning signals appurtenant to one of said lines of traffic and remote from said blocking 35 means and indicating danger when the line of traffic to which said signals appertain is blocked and the other line is clear, and means cooperating between said blocking means and warning signals for maintaining 40 said signals at danger in the event of failure of said blocking means to move to position for clearing the line of traffic to which said signals appertain and blocking the other line of traffic.

45. 12. In a safety device for intersecting passages for traffic, in combination, posts successively axially rotatable in forward and reverse directions, gates secured to the posts and swingingly movable in forward and reverse directions by rotation of the posts, 50 warning signals remote from said gates, the gates, when the posts are rotated in one direction, being swingingly moved for clearing one of the intersecting passages and blocking 55 the other passage and when the posts are rotated in the reverse direction being swingingly moved for clearing the last mentioned passage and blocking the first mentioned passage, and electric means cooperating between 60 the posts and warning signals for operating the signals respectively to warn traffic in one passage in the event of failure of the gates to move to position for clearing said one passage and blocking the other passage.

65. 13. In a safety device associated with a

crossing formed by the intersection of a passage for track controlled traffic and a passage for road traffic, in combination, posts axially rotatable in forward and reverse directions, gates secured to the posts and swingingly movable by rotation of the posts for sequentially blocking and clearing the passage for track controlled traffic and the passage for road traffic, warning signals arranged along the line of passage of the track controlled 70 traffic and remote from said gates and appurtenant to said traffic, and means cooperating between the posts and said signals for maintaining the signals set as indicating danger for the track controlled traffic in the event of failure of the gates in their movement to block the road traffic and means to successively actuate said posts.

14. In a safety device associated with a crossing formed by the intersection of a passage for track controlled traffic and a passage for road traffic, in combination, posts axially rotatable in forward and reverse directions, gates secured to the posts and swingingly movable by rotation of the posts for blocking and clearing the passage for track controlled traffic and the passage for road traffic, a post and its gate being arranged on each side of the track controlled traffic, and means for rotating the posts, said means being adapted for 95 rotating one of the posts to swing its gate in advance of the rotation by said means of the other post and the swinging of the gate of the other post for preventing interference between the gates in their swinging movement. 100

15. In a safety device associated with a crossing formed by the intersection of a passage for track controlled traffic and a passage for road traffic, in combination, posts axially rotatable in forward and reverse directions, 105 gates secured to the posts and swingingly movable by rotation of the posts for blocking and clearing the passage for track controlled traffic and the passage for road traffic, electrically operable means for rotating the posts, 110 and electric contacts arranged in the line of passage of the track controlled traffic and operatively connected to said electrically operable means for operating the same, a post and its gate being arranged on each side of 115 the track controlled traffic and said contacts being adapted for operating said electrically operable means to rotate one of said posts to swing its gate in advance of the rotation by said means of the other post and the swinging 120 of the gate of the other post for preventing interference between the gates in their swinging movement.

16. In a safety device associated with a crossing formed by the intersection of a passage for track controlled traffic and a passage for road traffic, in combination, posts axially rotatable in forward and reverse directions, a motor for each of the posts for rotating the post, gates secured to the posts and swing- 125 130

- ingly movable by rotation of the posts for blocking and clearing the passage for track controlled traffic and the passage for road traffic, and means for operating the motors for rotating the posts, a post and its gate being arranged on each side of the track controlled traffic and said means being adapted for operating the motor for rotating one of said posts to swing its gate in advance of operation by said means of the motor for rotating the other post and swinging of the gate of the other post for preventing interference between the gates in their swinging movement.
- 15 17. In a safety device associated with a crossing formed by the intersection of a passage for track controlled traffic and a passage for road traffic, in combination, a source of supply of electricity, posts axially rotatable in forward and reverse directions, gates secured to the posts and swingingly movable by rotation of the posts for blocking and clearing the passage for track controlled traffic and the passage for road traffic, electrical-
- 20 ly operable means for rotating the posts, electric contacts arranged in the line of passage of the track controlled traffic between the tracks thereof and operatively connected to said electrically operable means for operating
- 25 the same, and an electric switch located between said tracks and operatively connected to the source of electricity and to said contacts and operable by means appurtenant to a vehicle travelling in the line of passage of the
- 30 track controlled traffic.
18. In a safety device associated with a crossing formed by the intersection of a passage for track controlled traffic and a passage for road traffic, in combination, a source of supply of electricity, posts axially rotatable in forward and reverse directions, gates secured to the posts and swingingly movable by rotation of the posts for blocking and clearing the passage for track controlled traffic and the passage for road traffic, electrically operable means for rotating the posts, warning signals supported by the posts and common to both the passages for traffic and operable by rotation of the posts, warning sig-
- 35 nals arranged along the line of passage of the track controlled traffic and appurtenant to said passage and operated by rotation of the posts, electric contacts arranged in the line of passage of the track controlled traffic
- 40 and operatively connected to said electrically operable means for operating the same, and an electric switch operatively connected to the source of electricity and to said contacts and operable by means appurtenant to a ve-
- 45 hicle travelling in the line of passage of the track controlled traffic, said vehicle being provided with means for contacting said electric contacts during passage of said vehicle for operating the contacts.
- 50 19. In a safety device associated with a
- crossing formed by the intersection of a passage for track controlled traffic and a passage for road traffic, in combination, posts axially rotatable in forward and reverse directions, gates secured to the posts and swingingly movable by rotation of the posts for blocking and clearing the passage for track controlled traffic and the passage for road traffic, electric warning signals arranged along the line of passage of the track controlled traffic and remote from the gates, and electric means cooperating between the posts and said distant signals for operating said signals by rotation of the posts, and automatically operable means to successively actuate said posts.
- 55 20. In a safety device for road crossings, the combination of means successively movable for blocking a road at the crossing; means appurtenant to one of the roads remote from the blocking means for automatically successively controlling the blocking means; and signal means appurtenant to one of said roads and remote from the blocking means and controlled by the blocking means.
- 60 21. In a safety device for road crossings, the combination of means successively movable for blocking a road at the crossing; means appurtenant to one of the roads remote from the blocking means for successively controlling the blocking means; and signal means appurtenant to said last named road remote from the blocking means and controlled by the blocking means.
- 65 22. In a safety device for road crossings, the combination of a single pair of successively movable gates at opposite sides of both roads of the crossing for blocking the road at the crossing and closer to each other than the width of the gate; means for automatically successively actuating the gates.
- 70 23. In a safety device for road crossings, the combination of a pair of successively movable means on opposite sides of said crossing for blocking the road at the crossing; and a pair of means appurtenant to said road remote respectively different distances from the crossing and operable by a passing vehicle for respectively successively operating the blocking means respectively.
- 75 Signed at New York, in the county of New York and State of New York, this 22nd day of September, A. D. 1924.
- 80 ALBERT BIGIO.
